(57) **CLAIM**

the ornamental design for an inflatable sleeping pad, as shown.

DESCRIPTION

FIG. 1 is a front elevational view of an inflatable sleeping pad showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.
